Robert T. Casey
ATTORNEY

the cooperating halves 23 and 24 of the casing of the circuit breaker 17, see FIGURE 2.

As shown particularly in FIGURES 3 and 4, the locking tang 22 includes a first portion trapped between the halves of the circuit breaker casing and overlying a portion of the mounting lug 21, and a second portion projecting outwardly and downwardly of the circuit breaker casing.

The supporting pan 10 also includes locking strips 12A which are attached to the respective flanges 12 by means of a screw 12B, see FIGURE 5. The locking strips 12A extend along the underside of the corresponding flanges 12 in such a position as to partially close the openings 16 under the retaining hooks 15 as shown, for example, in FIGURE 3.

Assembly of circuit breakers on the panel assembly of the present invention is carried out as follows. The locking strips 12A are removed from the flanges 12. Circuit breakers 17 of various desired ratings, are mounted in place on the panel by tilting the breaker so as to insert the locking tang in a corresponding opening 16, and to cause the corresponding hook 15 to enter the recess 20 and to overlie a portion of the locking tang 22. (The right hand breaker of FIGURE 1 as shown in such an initially positioned arrangement.) The breaker is then rotated about its engagement with the hook 15 so as to bring the socket 18 into plug-in engagement with a portion of a corresponding contact blade 13. In this fully mounted position, the hook 15 overlies a portion of the locking tang 22. (The left hand breaker of FIGURE 1 is shown in such a fully mounted position.) When all desired circuit breakers have been mounted, the locking strips 12A are mounted in place, such as by means of special screws 12B as shown in FIGURE 5. When the circuit breaker is in fully mounted position, and the locking strip 12A is also in mounted relation, the parts occupy the positions as shown in FIGURE 3. It will be seen from this figure that because of the presence of the locking strip 12A, it is not possible to rotate a circuit breaker 17 upwardly so as to remove the plug-in 40 socket 18 from the contact blade 13. All breakers are thus securely locked in place and cannot be removed without removing the locking strips 12A. Removal of the locking strips 12A, however permits easy removal of the circuit breaker, as shown in FIGURE 4, and ready replacement.

The screw 12B is preferably a special head type so as to render it difficult for the ordinary user or other unauthorized person to remove the locking strip 12A. Other locking devices may, of course, be utilized, including the provision of matching holes in the mounting strip and flange to permit the insertion of a small padlock or customary wire and lead seal.

In the embodiment of the invention shown in FIGURES 6-8, a similar supporting pan 30 is provided having the contact blades 13 and insulating members 14 supported on the back wall 31 thereof and having outwardly directed flanges 32. Each of the flanges 32 has a series of small openings 33 therein, see FIGURES 7 and 8, disposed in a row along the outer edge of the flange 32.

The circuit breaker 17A similarly is provided with a socket, not shown, for engaging the contact blade 13 and a recess 34 in the opposite corner. In this form of the invention, two types of circuit breakers are provided, as indicated at 17A in FIGURES 6 and 7 and 17B in FIGURE 8. The circuit breakers 17A are as previously described but include an offset mounting tang 35 which can be inserted and removed regardless of the presence or absence of the locking strip 36. In other words, the mounting tang 35 performs a holding function for this end of such circuit breakers comparable to that performed by the hooks 15 in the first embodiment.

The circuit breakers 17B are provided with a combination mounting and locking tang 37 which is somewhat

similar to the mounting tang 35, but which terminates in a return-bent tubular portion 38. The portion 38 of the tang 37 prevents removal of the circuit breaker 17B while the locking strip 36 is in place, since it cannot pass through the restricted opening. When the locking strip 36 is removed, however, it is possible to readily remove the circuit breakers 17B since the portion 38 will then easily pass through the opening 33. It will be understood that while a tubular portion has been shown, any suitable enlargement may be utilized. For instance, a partial return-bend or "hook" may be used. Such a formation could not be brought through the opening 33, while the locking strip 36 is in place, since the panel enclosure would make it impossible to rotate a breaker far enough.

Since no dangerous overloading conditions can be caused by the use of the lowest rated breakers, such for example as 15 amperes breakers, such breakers are preferably constructed as shown in 17A. Circuit breakers having higher ratings, however, such for example as 20 amperes and upward, are made as shown in 17B.

While the invention has been shown and described in only two specific embodiments, it will be readily appreciated that many modifications thereof may be made, and it is therefore intended by the appended claims to cover all such modifications as fall within the true spirit and scope of the invention. For example, while the invention has been described as applied to an electric circuit breaker panelboard and electric circuit breakers, it will be readily apparent that the same may be used with other electric circuit controlling devices, such for example as switches and fuses or fuse blocks, which have mounting characteristics similar to those of the electric circuit breakers pictured.

What I claim as new and desire to secure by Letters Patent of the United States is:

1. An electric control device panel assembly comprising:

- (a) a support having a generally planar supporting portion,
- (b) a row of apertures in said supporting portion, each of said apertures being located at a control device mounting location,
- (c) a retaining hook adjacent each of said apertures and including a first portion extending substantially perpendicular to the plane of said supporting portion and a second portion extending substantially parallel to the said plane over said aperture,
- (d) at least one control device mounted on said support and including a portion disposed and arranged to be received under said retaining hook when said control device is in said mounting location,
- (e) said control device including a locking projection disposed and arranged to project through one of said apertures when said control device is in said mounting location,
- (f) a locking strip mounted at the underside of said supporting portion by releasable mounting means and movable between a locking position and a releasing position, said locking strip when in said locking position including a portion disposed and arranged to obstruct movement of said projection in said aperture whereby to prevent movement of said control device in removing direction.

2. An electric control device panel assembly comprising:

- (a) a support having a generally planar supporting portion,
- (b) a plurality of aligned apertures in said support, each of said apertures being located at a control device mounting location,
- (c) a plurality of aligned retaining hooks on said supporting portion, each of said retaining hooks being positioned adjacent a corresponding one of said apertures and each of said retaining hooks including a portion extending substantially perpendicular to

- the plane of said supporting portion and a second portion extending substantially parallel to the plane of said supporting portion over said corresponding aperture,
- (d) a plurality of stationary plug-in type contacts mounted on said support, each of said contacts being located in spaced substantially co-planar relation with a corresponding one of said retaining hooks, 5
- (e) at least one control device comprising a generally rectangular insulating casing having a back wall and opposed end walls, 10
- (f) said control device including a plug-in type electrical contact adjacent said back wall and one of said end walls and a mounting portion adjacent said back wall and the other of said end walls, 15
- (g) said control device being mounted on said supporting portion by engaging said mounting portion under one of said retaining hooks with said back wall in angular relation to the plane of said supporting portion and rotating said control device about said hook to bring said control device plug-in contact into plug-in type electrical engagement with said stationary contact and to bring said back wall into substantially parallel relation with said plane of said supporting portion, 20
- (h) a locking projection fixedly attached to said insulating casing adjacent said mounting portion and including a depending portion projecting below said bottom wall, said depending portion of said locking projection extending through one of said apertures 25 when said circuit breaker is in mounted position,
- (i) a locking strip mounted at the underside of said supporting portion by releasable mounting means, said locking strip including a portion limiting movement of said locking projection in said aperture, 30 whereby to prevent reverse rocking movement of said control device to the extent necessary to disengage said control device plug-in type contact from said stationary contact, and whereby said mounting portion of said casing and said locking projection combine to prevent disengagement of said casing from said retaining hook while said locking strip 35 is in said locking position.
3. An electric control device panel assembly comprising:
- (a) a support having a generally planar supporting portion,

- (b) a plurality of aligned apertures in said supporting portion, each of said apertures being positioned at a corresponding control device mounting location,
- (c) a plurality of stationary plug-in type contacts carried by said support, each of said contacts being positioned in spaced relation with a corresponding one of said apertures,
- (d) at least one first electric circuit control device comprising a generally rectangular insulating casing having a bottom wall and opposed end walls, and a mounting projection carried by said insulating casing adjacent said bottom wall and adjacent one of said end walls, said mounting projection including a portion projecting below said bottom wall, said mounting projection having an enlarged portion adjacent the outer end thereof, said enlarged portion being adapted to pass through one of said apertures when said circuit breaker is placed in mounted position on said panel,
- (e) at least one second electric circuit control device comprising a generally rectangular insulating casing having a bottom wall and opposed end walls, and a mounting projection carried by said insulating casing adjacent said bottom wall and adjacent one of said end walls, said mounting projection including a portion projecting below said bottom wall, said mounting projection having no enlarged portion adjacent the outer end thereof,
- (f) and a locking strip removably mounted at the under side of said supporting portion and including portions overlying portions of said apertures and restricting said apertures sufficiently to prevent removal of said mounting projection of said first control device while permitting removal of said mounting projection of said second control device when said locking strip is in mounted position.
